DESIGN FOR A NEGLIGEE OR SIMILAR ARTICLE

Mary Tutundgy, New York, N. Y.

Application October 21, 1940, Serial No. 95,963

Term of patent 7 years

To all whom it may concern:

Be it known that I, Mary Tutundgy, a citizen of the United States of America, residing in New York city, in the Borough of Manhattan, county and State of New York, have invented a new, original, and ornamental Design for a Negligee or Similar Article, of which the following is a specification, reference being had to the accompanying drawing, forming part thereof, wherein my new design with the detachable skirt portion in partially open position;

Figure 2 is a rear view of the negligee shown in Figure 1, on a smaller scale.

The jacket portion of the negligee is of heavy pile fabric.

I claim:

The ornamental design for a negligee or similar article, substantially as shown and described.

MARY TUTUNDGY.
